UNITED STATES PATENT OFFICE

122,730

DESIGN FOR A CHAIR OR SIMILAR ARTICLE

Rubin Union and Philip Union, Baltimore, Md.

Application February 9, 1940, Serial No. 90,168

Term of patent 3½ years

To all whom it may concern:

Be it known that we, Rubin Union and Philip Union, citizens of the United States, residing at Baltimore, Maryland, have invented a new, original, and ornamental Design for a Chair or Similar Article, of which the following is a specification, reference being had to the accompanying drawing, forming part thereof.

In the drawing, Figure 1 is a perspective view of a chair showing our new design; and Figure 2 is an enlarged fragmentary detail of the arm post portion thereof.

The rear of the chair is substantially plain and the other side is similar to the one shown.

We claim:

The ornamental design for a chair or similar article, as shown and described.

RUBIN UNION.
PHILIP UNION.
